Inventor.

Elihu Spencer.

United States Patent Office.

ELIHU SPENCER, OF ELIZABETH, NEW JERSEY, ASSIGNOR TO ROBERT WESCOTT, OF SAME PLACE.

Letters Patent No. 75,655, dated March 17, 1868.

IMPROVEMENT IN WATER-METERS.

The Schedule referred to in these Letters Patent and making part of the same.

TO ALL WHOM IT MAY CONCERN:

Be it known that I, ELIHU SPENCER, of Elizabeth, county of Union, and State of New Jersey, have invented a new and useful Improvement in Water-Meters, or Meters for Measuring Liquids; and do hereby declare that the following is a full, clear, and exact description thereof, reference being had to the accompanying drawings, forming part of this specification, of which—

Figure 1 is an elevation of a water-meter and case, the covers of the case and valve-chamber being removed.

Figure 2, an external end elevation.

Figure 3, a horizontal section through the cylinders and valve-chest; and

Figures 4 and 5 transverse and vertical sections of portions of my invention.

This invention relates to a water-meter, in which the case or box containing the operating parts is so constructed as to form the heads of the cylinders and render the box itself water-tight, whereby the use of stuffing-boxes for the piston-rods and valve-stems used in my former (patented) invention are dispensed with, and a consequent increase of power derived from the force or action of the water on the pistons, with other advantages to be hereinafter explained.

In the drawings, A represents the box, whose base, B, rests on and forms the upper heads of the cylinders. C is a plate, which constitutes the lower heads of the cylinders, said plate being bolted to the base, B, of the box by bolts $z z$, firmly securing the cylinders D D and valve-chest E placed between the said box and plate. These cylinders and valve-chest, instead of being let into the parts B C, as represented, may have flanges at top and bottom for reception of rubber packing between them and their heads, or the cylinders and valve-chest may be cast on the lower plate C, if preferred. f f are the pistons; g g, the piston-rods, which slide freely in guides h h, cast on the box A. i i are rods, which connect the piston-rods with the arms of the crank-shaft K, said shaft being also supported in bearings k k, cast on the box. l l are the slide-valves within the chest E. m m¹ m² m³ are the ports of injection and discharge through which the water from the supply-pipe y is admitted and discharged from the cylinders through the pipe z. n n are the valve-stems, and o o eccentrics and rods connecting the valves with the crank-shaft K. On the crank-shaft K is placed a worm-wheel, p, which, with the pinion q and shaft r, (passing through a stuffing-box, s,) actuates clock-mechanism placed on top of the box for recording the quantity of water passed through the meter.

Having discovered, from use of the water-meter for which I obtained a patent, June 12, 1866, that the stuffing-boxes and slotted piston-rods used therein tended to impede the action or force of the water on the pistons, and the form of box, while it consumed much stock, was subject to leakage; these defects prompted me to design the present invention, which I consider an improvement on the former, inasmuch as the disuse of the stuffing-boxes to the piston-rods and valve-stems, as well as substituting connecting-rods between the crank and piston-rods, for the slotted heads on the piston-rods, whereby I am enabled to remove much friction and render the pistons more sensitive to the force or action of the water thereon; and, besides this, the box is water-tight and more compact; and thus I produce a superior water-meter and at much less cost.

What I claim as my invention, and desire to secure by Letters Patent, is—

Constructing the box containing the operating parts of the meter, so as to form the heads of the cylinders and render the box itself water-tight, substantially as and for the purposes herein specified.

I also claim the arrangement of the piston-rods g g, in the free guides h h, in combination with connecting-rods i i, substantially as and for the purpose set forth.

In testimony whereof, I have hereunto set my signature, this eleventh day of December, A. D. 1867.

ELIHU SPENCER.
